[57] CLAIM

The ornamental design for an earplug assembly, as shown and described.

DESCRIPTION

FIG. 1 is a perspective view of an ear plug assembly showing my new design;

FIG. 2 is a perspective view of an ear plug taken at an enlarged scale;

FIG. 3 is a side elevation thereof; and

FIG. 4 is a perspective as seen from the end opposite FIG. 2.

The broken lines representing the eyeglass frame are shown for illustrative purposes only.

The earplug assembly of my invention is generally symmetrical, so that any side not visible in the figures has an appearance like that of those sides which are more fully shown.
